ART OF CRACKING HYDROCARBONS.

Application filed May 15, 1925. Serial No. 30,404.

This invention relates to improvements in the cracking of heavier hydrocarbon oils, such as gas oil or kerosene, to produce lighter hydrocarbon oils, such as gasoline or pressure distillate, therefrom. More particularly, the invention relates to improvements in the operation of externally heated single pass tubular oil cracking still and in the operation of heating furnaces employed in conjunction with cracking stills of this type. This application is in part a continuation of my prior application filed August 28, 1922, Serial No. 584,711.

In a single pass tubular oil cracking still, the oil is passed but once through the oil heating tubes and the entire heat input to the oil is effected in the single passage of the oil through the heating tubes, the oil supplied to the still being brought from its initial temperature to the cracking temperature employed in the single passage of the oil through the heating tubes. For efficiency of operation and economy of equipment, it is desirable to transfer the maximum amount of heat to the oil in a minimum distance of oil travel. For effecting this heat transfer, however, it is desirable to employ heating gases at temperatures which do not tend to cause overheating and which do not impose severe strains on the still equipment. Hitherto, these apparently contrary factors have prevented development of maximum heating efficiency in externally heated single pass tubular oil cracking stills. Moreover, with the usual fuels, e. g. gas or fuel oil or coal, temperatures promoting efficient combustion are substantially higher than the temperatures at which it is desirable to have the heating gases contact with the oil heating tubes of the cracking still. Here also, previous proposals to reduce the temperature of the heating gases passing over the oil heating tubes, e. g. dilution of the hot products of combustion with cold air or carrying out the combustion with a large excess of air, have involved a decrease in heating efficiency.

One of the objects of the present invention is to provide an improved method of heating externally heated single pass tubular oil cracking stills in which high average temperature differentials are maintained between the heating gases and the oil circulating through the heating tubes in a single pass, promoting effective heat transfer with-

out prolonged oil travel and without employing heating gases at excessive temperature in contact with the oil heating tubes, and also in which the heating gases passing over the oil heating tubes are tempered while maintaining a high temperature of combustion, without decreasing but rather increasing the efficiency of the heating operation.

According to the present invention, the oil heating tubes of the cracking still are arranged in a heating furnace through which hot products of combustion are circulated from a fire-box in which fuel is burned for supplying heat to the cracking operation, the oil undergoing cracking is circulated through the oil heating tubes in a single pass, and part of the heating gases which have passed over the oil heating tubes in the heating furnace are recirculated and admixed with the fresh hot products of combustion, the resulting mixture of heating gases being passed over the oil heating tubes in the furnace.

The oil circulated through the heating tubes in a single pass may be discharged into a drum or shell or other suitable receptacle or reservoir in which the cracking operation is continued or in which another cracking operation is carried out, or the cracking operation may be substantially completed in the oil heating tubes in the furnace. The vapors of the cracked oil may also be subjected to a refluxing operation and the reflux may with advantage be circulated in a single pass through the oil heating tubes in admixture with the fresh oil. Circulation of the oil through the heating tubes is advantageously maintained in a generally countercurrent direction to the flow of heating gases over the heating tubes. The combustion of the fuel employed may be carried out at as high a temperature as is desired for efficient combustion of the fuel, and it is also advantageous to effect the combustion without substantial excess of air to further improve the fuel economy.

The invention will be further described in connection with the accompanying drawings which illustrate in a diagrammatic and conventional manner, in elevation and partly in section, an apparatus adapted for the practice of the process of the invention, but it is intended and will be understood that this further description and illustra-

tion are for the purpose of exemplification and that the invention is not limited thereto.

In the drawings, a single pass externally heated tubular cracking still is shown discharging into a shell still or reservoir from which the vapors of the cracked oil are taken off. The single pass cracking still comprises a furnace 1 in which a battery of heating tubes 2 are arranged, oil being supplied to the heating tubes through connection 3 and after passing in a single pass therethrough being discharged through connection 4. The heating furnace 1 is provided with a fire-box 5 and a stack flue 6, heating gases being circulated from the fire-box through the heating furnace over the oil heating tubes therein to the stack flue. The fire-box 5 is provided with means for burning the fuel employed to supply the heat used in the cracking operation. A burner for gaseous or liquid fuel is shown at 6. Before the hot products of combustion from the fire-box 5 come in contact with the oil heating tubes 2 in the furnace 1, they are admixed with a part of the heating gases which have passed over the oil heating tubes and which are returned through connection 7. The connection 7 is provided with an inlet 8 adjacent the exit to the stack flue from the furnace 10 and with an outlet 9 through which the heating gases withdrawn from near the outlet of the furnace are returned and admixed with the hot products of combustion. The return connection 7 includes a blower 10 which may be operated by a steam jet 11 or other suitable means for maintaining circulation of the returned heating gases. In place of the blower shown, a fan or other suitable forcing means may be employed. The fresh hot products of combustion are thus diluted with the recirculated cooler gases which have passed over the oil heating tubes and are thereby tempered before the resulting mixture of heating gases is passed over the oil heating tubes. At the same time, the temperature of combustion in the fire-box 6 may be regulated more or less independently of the temperature conditions which it is desired to maintain in the heating furnace proper.

In the apparatus illustrated, the oil discharged from the single pass cracking still through connection 4 is introduced into the reservoir 12 through pipe 13. Vapors from the shell still escape through connection 14 to dephlegmators 15 and 16. Vapors escaping from dephlegmator 16 through connection 17 are discharged to a condenser (not shown) in which the vapors of the cracked oil are condensed. Pressure in the cracking system may be maintained and regulated by a valve 18 arranged between the shell still and the dephlegmators, or by a valve 19 arranged between the dephlegmators and the condenser, or by suitable valves arranged

beyond the condenser. A connection 20 is shown for withdrawing tar and residue from the shell still 12. The unvaporized residue of the oil discharged into the reservoir from the single pass tubular cracking still may be withdrawn through this connection. Additional fresh oil, particularly oil of a heavier character than that passed through the heating tubes of the single pass cracking still, may also be supplied to the reservoir and subjected to a cracking operation therein by the heat of the products discharged from the single pass cracking still. Oil so supplied to the reservoir may be pumped from a receptacle 21 through the dephlegmators 15 and 16 in indirect heat exchanging relation with the vapors therein for cooling and dephlegmating the vapors and thence into the reservoir through connection 22 and the pipe 23. Reflux from the dephlegmators 15 and 16 may be discharged to the receptacle 24, or the heavier reflux from the dephlegmator 15 may be returned to the reservoir through connection 25. This reflux may with advantage be pumped in a single pass through the heating tubes 2 in the single pass cracking still by means of pump 26 together with fresh oil supplied to the single pass cracking still from the receptacle 27. Reflux may be so returned while still warm. The reservoir may be heated by means of furnace 28 in addition to the heat supplied internally by the hot products discharged from the single pass cracking still, or it may be heated internally only by the hot products discharged from the single pass cracking still. The reservoir, particularly where it is heated internally only by the hot products discharged from the single pass cracking still, and the connections between the single pass still and reservoir may with advantage be lagged to prevent heat loss.

In the heating furnace of the single pass cracking still, the temperature of the gas mixture first contacted with the oil heating tubes is decreased and the temperature of the heating gases escaping from the heating furnace are increased as the rate of recirculation of heating gases through connection 7 is increased. The temperature conditions within the heating furnace may thus be conveniently controlled by regulating the rate of recirculation of heating gases. This control, moreover, is largely independently of the temperatures maintained in the fire-box 5, so that in the fire-box temperatures most suitable for efficient combustion of the fuel burned can be employed. In operation, for example, the temperature of the oil discharged from the single pass cracking still may vary from about 700° to 1200° F. At the same time, while maintaining a combustion temperature of as much as 2100° to 2700° F. or more, the temperature of the heating gases, including the

hot products of combustion from the firebox and the recirculated heating gases, as they first contact with the heating tubes may be maintained in the neighborhood of 900° to 5 1500° F. by recirculating cooler heating gases from near the exit of the heating furnace and admixing them with the fresh hot products of combustion. The temperature of the heating gases leaving the heating furnace 10 through the stack flue 6 may approximate 450° to 700° F. or more in such operations. It will be understood that the foregoing temperatures are given as illustrations of the conditions which may be maintained in 15 the heating furnace in carrying out the process of the invention and that the invention is not limited thereto. These temperatures described as illustrating the invention were maintained while using gas, or 20 gas and fuel oil, as fuel in operations in which charging stock of a kerosene character, or somewhat heavier charging stock of a gas oil character, or including in addition reflux constituents, were circulated in 25 a single pass through the oil heating tubes in the heating furnace.

The recirculated heating gases may be admixed with the hot products of combustion in the fire-box, or they may be admixed 30 with the hot products of combustion before or as they pass over the single pass oil heating tubes. The heating gases in either case are thus tempered in an advantageous way with improvement of the heating operation 35 while an amount of fuel is saved corresponding approximately to the amount of heat which would be necessary to raise a cold diluent, e. g. cold air, to the temperature of the recirculated heating gases in addition 40 to the amount saved because of the improved efficiency of the heating operation itself. Where part of the heating gases which have passed over the oil heating tubes are returned directly to the fire-box the temperatures in the fire-box may be somewhat 45 reduced and all or part of the recirculated heating gases may thus be introduced into the fire-box proper, for example through ports in the walls of the fire-box, to assist in 50 protecting the fire-box construction. The temperature of the actual combustion may nevertheless be maintained at a high value, but, even where the temperature of combustion is somewhat reduced, the economies 55 in fuel and the improvement in efficiency which are effected by the relatively high temperature at which the diluent, i. e. the recirculated heating gases, are introduced and the increase in volume of the heating 60 gases circulating over the single pass oil heating tubes are secured.

The present invention has several important advantages. It will be apparent that in carrying out the invention the fuel 65 economy is improved in several ways. By

providing for tempering of the heating gases passing over the oil heating tubes in the single pass cracking still by recirculation of part of the heating gases which have passed over the oil heating tubes, high combustion temperatures at which efficient combustion of the fuel is secured may be employed without detriment to the cracking operation carried out in the single pass heating tubes and without imposing severe 70 strains on the still equipment. A high average temperature differential between the heating gases and the oil circulating in a single pass through the heating tubes may be maintained, without subjecting the heating tubes to heating gases at excessive temperatures, further promoting the effectiveness of the heat transfer. Likewise, the recirculation of part of the heating gases which have passed over the heating tubes increases the 75 volume and hence the velocity of flow of the heating gases, further improving the efficiency of the heat transfer. As compared to an operation in which excess cold air is employed to dilute the products of combustion, the heat necessary to raise the temperature of the cold air to the temperature at which the heating gases are discharged from the heating furnace is saved. While 80 in carrying out the invention the temperature at which the heating gases escape is increased, the amount of heating gases escaping may be reduced so that the amount of heat escaping with the heating gases which are not recycled may not be increased but 85 may even be somewhat decreased. All of these improvements assist in reducing the amount of fuel required. Also, by improving the efficiency of the heat transfer and by 90 maintaining a high average temperature differential throughout the heating operation between the heating gases and the oil circulating in a single pass through the heating tubes, the amount of heat which can be transferred to the oil in a given distance of oil travel is substantially increased although excessively high temperatures are 95 at the same time avoided. Due to the improved uniformity of the heating operation, higher temperatures may also be employed in the heating furnace where desired. Another advantage of the invention is the improved control of the heating operation which it affords.

In referring herein to a single pass cracking still or a single pass cracking operation, it will be apparent from the drawings and from the foregoing description that the improvement relates particularly to cracking operations in which the fresh oil supplied is circulated but once through the oil heating tubes of the still. The invention includes operations in which vaporized fractions are refluxed and recirculated through the oil heating tubes, but it is to be distinguished 100

from operations in which the fresh oil itself or any unvaporized portion thereof is recirculated through the heating tubes.

I claim:

- 5 1. In the operation of externally heated single pass tubular oil cracking stills, the improvement comprising forcing a stream of oil once through an elongated heating conduit, burning fuel and circulating the hot products of combustion over the oil heating tubes in a direction generally countercurrent to the flow of oil therethrough, whereby the temperature of the heating gases last contacting with the heating conduit is reduced to below the temperature at which the hot oil products are discharged from said heating conduit, recirculating part of the said heating gases which have passed over the oil heating tubes and admixing them with the fresh hot products of combustion and circulating the resulting mixture of heating gases over the oil heating tubes.
- 10 15 20 25 30 35 40 45 50 55 60 65 1. In the operation of externally heated single pass tubular oil cracking stills, the improvement comprising forcing a stream of oil once through an elongated heating conduit, burning fuel and circulating the hot products of combustion over the oil heating tubes in a direction generally countercurrent to the flow of oil therethrough, whereby the temperature of the heating gases last contacting with the heating conduit is reduced to below the temperature at which the hot oil products are discharged from said heating conduit, recirculating part of the said heating gases which have passed over the oil heating tubes and admixing them with the fresh hot products of combustion and circulating the resulting mixture of heating gases over the oil heating tubes.
2. In the operation of externally heated single pass tubular oil cracking stills, the improvement comprising forcing a stream of oil once through an elongated heating conduit, burning fuel without any substantial excess air and circulating the hot products of combustion over the oil heating tubes in a direction generally countercurrent to the flow of oil therethrough, whereby the temperature of the heating gases last contacting with the heating conduit is reduced to below the temperature at which the hot oil products are discharged from said heating conduit, recirculating part of the said heating gases which have passed over the oil heating tubes and admixing them with the fresh hot products of combustion and circulating the resulting mixture of heating gases over the oil heating tubes, subjecting the vapors of the cracked oil to a refluxing operation, and circulating reflux therefrom through the oil heating tubes in a single pass in admixture with the fresh oil.

In testimony whereof I affix my signature:

EDWARD W. ISOM.
